UNITED STATES PATENT OFFICE.

HENRY A. HOUSE, JR., OF BUFFALO, NEW YORK, ASSIGNOR TO WIRE WHEEL CORPORATION OF AMERICA, OF BUFFALO, NEW YORK, A CORPORATION OF NEW YORK.

WHEEL.

1,313,988.

Specification of Letters Patent. Patented Aug. 26, 1919.

Application filed November 6, 1918. Serial No. 261,425.

To all whom it may concern:

Be it known that I, HENRY A. HOUSE, Jr., a citizen of the United States, and resident of Buffalo, Erie county, State of New York, 5 have invented certain new and useful Improvements in Wheels, of which the following is a specification.

This invention relates to improvements in wheels and particularly to improvements in 10 wire spoked wheels having two rims and a single hub. One object of this invention is to provide a wheel of this character which is adapted to resist shock from either side and in which the rims are firmly held at a 15 fixed distance from each other.

Another object of this invention is to provide a wire spoked double wire wheel in 20 which a broken spoke can be removed and a new one substituted therefor without disturbing the other spokes.

A further object of this invention is to provide a twin rim wheel in which the rims are independently supported and firmly held at a predetermined distance apart.

Other objects will appear from examination 25 of the specification and the drawing which forms a part thereof and in which Figure 1 is a side elevation of a wheel embodying this invention and Fig. 2 a section 30 taken on line 2-2 of Fig. 1.

Referring to the drawing the hub 10 comprises a hollow barrel 11, carrying at each end an annular member 12. As shown particularly in Fig. 2 the annular member 12 is 35 cut away at 13 to provide a sleeve portion which can be slipped over the end of the barrel 11. The member 12 has also an annular flange 14 extending away from the barrel, provided with two annular rows of holes 40 15 and 16. The holes in each row are the same in number and arranged in pairs, the pairs in the outer row alternating with the pairs in the inner row (see Fig. 1). In these holes are secured the spokes to which 45 reference will be made later.

The rims 17 and 18 are identical in construction and each is provided with two annular rows of openings through which the spoke engaging nipples 19 extend. It is to 50 be noted that the rows of openings in the rims are equally distanced from and on each side of the center line of the rim. For convenience in description the left side of rim 17 and the right side of rim 18 as shown in

Fig. 2, will be referred to as the outer sides 55 and the other sides as the inner sides.

The spokes are arranged in six sets, designated on the drawing as 20, 21, 22, 23, 24 and 25 respectively. Sets 20, 21 and 22 extend from the left end of the hub, the first 60 to the outer side of the adjacent rim 17, the second to the inner side of the adjacent rim 17 and the third to the inner side of the non-adjacent rim 18. Sets 23, 24 and 25 extend from the right end of the hub, the first to 65 the inner side of the non-adjacent rim 17, the second to the inner side of the adjacent rim 18 and the third to the outer side of the adjacent rim 18. Referring to drawing it will be seen that the wheel is exactly symmetrical and reversible.

The set 20 comprises the spokes A and B, the former extending from the outer row of holes 15 in the flange 14 and the latter from the inner row of holes 16. The sets 21, 22, 75 23 and 24 comprise respectively the spokes C, D, E and F, the spokes C and F extending from the outer row of holes 15 and the spokes D and E extending from the inner row of holes 16. The set 25 comprises the 80 spokes G and H, the former extending from the inner row of holes 16 and the latter from the outer row of holes 15. The spokes A, B, C, D, E, F, G and H are equal in number. A and C extend from row 15 and B and D 85 from row 16 in the left hand flange of Fig. 2, while F and H extend from row 15 and E and G from row 16 in the right hand flange of Fig. 2.

Fig. 1 is a view taken from the right side 90 of Fig. 2 and spokes A, B, C and D which extend from the rear flange are shown in dotted lines, while spokes E, F, G and H, which extend from the front flange are, 95 shown in full lines. The rims as pointed out above are identical in construction and the perforations are transversely in alignment. As a result the spokes going to the front rim and those going to the rear rim appear to meet at a point in pairs, see for 100 instance in Fig. 1 spokes E and G, F and A, H and C, and B and D.

All the spokes are inclined toward the center line of the wheel and of the spokes secured to each rim two sets are inclined in 105 the same general direction while the third is inclined in the other direction. The amount of inclination of the single set of spokes,

however, is so much greater than that of the other two sets that the rim is held in equilibrium and the tension on all the spokes is substantially the same while any side 5 shock is resisted by three quarters of the spokes in the rim.

Spokes D and E which comprise sets 21 and 22 cross at about the center line of the wheel thus forming a truss brace to prevent the 10 separation of the rims.

No spoke contacts with any other spoke so that there is no necessity of bending and moreover the insertion or removal of one spoke can be done without interfering with 15 the remaining spokes. This advantage flows from the staggered arrangement of the spoke holes 15 and 16 in the flanges 14 and from the particular inclination of the flanges.

20 While only one form of this invention has been shown and described, it will be understood that the invention is not limited to this particular embodiment and that other forms may be used without departing 25 from the spirit and scope of the invention as pointed out in the accompanying claims.

I claim:

1. A wheel having in combination a hub, 30 two rims, spokes extending from one side of each rim to the adjacent side of the hub and spokes extending from the other side of each rim to both ends of the hub.

2. A wheel having in combination a hub, 35 two rims and spokes extending from each end of the hub to both sides of the adjacent rim and one side of the non-adjacent rim.

3. A wheel having in combination a hub, 40 two rims and six sets of spokes in groups of three, one group attached to each end of the hub, and in each group one set extending

to the outer edge of one rim and the other two sets extending to the inner edges of each rim.

4. A wheel having in combination two 45 rims, a hub having an annular flange at each end, two annular sets of holes in each flange, spokes fastened in one set of holes extending to the outer and inner edges of one rim and spokes fastened in the other 50 set of holes extending to the outer edge of one rim and the inner edge of the other rim.

5. A wheel having in combination two 55 rims, a hub having an annular flange at each end, two annular sets of an equal number of holes in each flange, spokes fastened in the outer set of holes extending to the outer and inner edges of the adjacent rim and spokes fastened in the inner set of holes 60 extending to the outer edge of the adjacent rim and the inner edge of the non-adjacent rim.

6. A wheel having in combination two 65 rims, a hub, spokes extending from the outer edges of the rims to the adjacent ends of the hub and an equal number of spokes extending from the inner edges of the rims to both ends of the hub.

7. A wheel having in combination two 70 rims, a hub, spokes extending from the outer edges of the rims, to the adjacent ends of the hub and an equal number of spokes extending from the inner edges of the rims to both ends of the hub, the spokes extending to the same end of the hub being inclined in the same general direction and the 75 spokes extending from the inner edges of each rim to the non-adjacent end of the hub crossing at the center line of the hub to form a truss brace.

In testimony whereof I affix my signature.

HENRY A. HOUSE, JR.
